UNITED STATES PATENT OFFICE.

CHARLES H. HODGKINS, OF PITTSBURGH, AND FRED M. PARKS, OF MURRYSVILLE, PENNSYLVANIA, ASSIGNEES TO WESTINGHOUSE ELECTRIC AND MANUFACTURING COMPANY, A CORPORATION OF PENNSYLVANIA.

LIMIT SWITCH.

Application filed June 25, 1920. Serial No. 391,624.

Our invention relates to switches, and particularly to limit switches such as are employed in combination with controllers for motors used in operating crane machinery.

5 An object of our invention is to provide a switch mechanism that will automatically interrupt the circuit through the operating motor when the apparatus driven thereby has reached a limit of movement.

10 Another object is to provide a switch mechanism having the above characteristics wherein the movable switch member is moved into and out of engagement with the contact members with a snap, thereby avoiding destructive arcing.

Another object is to provide a switch mechanism wherein the switch is positively retained in engagement with a contact member or held out of engagement therewith 20 until the switch-member-actuating means has moved a determined distance, and wherein the switch member is actuated with a snap.

Another object is to provide a switch 25 mechanism of the double-throw type wherein the switch member separately engages the contact members and is positively held in engagement with the contact members until the switch-member-actuating means has moved 30 a determined distance and wherein the switch member is withdrawn from one contact member and moved into engagement with the other contact member with a snap after said determined movement of the 35 switch-actuating means.

Another object is to provide a switch mechanism of the double-throw type wherein the switch member is moved into contact with one member by a gravity-actuated member and into engagement with the other contact member by a yielding means, the tension of which is normally overcome by the gravity-actuated member and whereby the switch member is made responsive to 45 the variations of the load upon the gravity-actuated member.

These and other objects are attained by means of apparatus embodying the features herein described and illustrated in the accompanying drawings.

Referring to the drawings illustrating one embodiment of our invention, Fig. 1 is a transverse section through the switch mechanism taken on the line I—I of Fig. 2.

Fig. 2 is a side elevation of the switch mechanism with the cover removed and showing the switch operating mechanism and the contact members.

Fig. 3 is a front elevation of a complete switch member.

Fig. 4 is a side elevation of a complete switch element showing a pair of switch members mounted thereon.

Fig. 5 is an end elevation of the switch casing and the exposed operating apparatus.

Fig. 6 is an elevational view of certain elements of the switch mechanism showing the relative positions occupied by the elements during various stages of their operations.

Fig. 7 is an elevational view similar to that of Fig. 6, showing the relative positions of certain elements of the switch mechanism after the switch member has been moved from its original position and into engagement with the opposite contact members.

Fig. 8 is a diagram illustrating the connections of the limit switch with the controller and motor circuit.

Referring to the drawings, the apparatus includes a box comprising a cover 8 and end walls 9 and 10 which are preferably cast integral with the bottom 11 of the box. The cover is preferably made of sheet metal which is so formed that it fits snugly between the end walls and is supported upon the inwardly projecting flanges 12 bordering the periphery thereof. The switch mechanism includes a pair of separate insulated contact supporting bars 13 and 14 extending longitudinally of the box and arranged in parallel relation. The bars are supported upon the end plates or walls 9 and 10 and carry the contact units 15 and 16, respectively. Any desired number of contact units may be arranged in spaced relation upon the bars 13 and 14 and, in the present embodiment of the invention, two units of a well known type are mounted in spaced relation upon each bar. Each contact unit includes the usual blowout coil 17, contact terminal 18, and a stationary contact member which is disposed between the arc shields 19.

For the purpose of illustration, the contact members of the units 15 and 16 are

- designated by the numerals 20 and 21, respectively, and, as illustrated in Fig. 1, occupy positions on opposite sides of the axis of the switch shaft 22 which extends longitudinally of the box 8. The shaft 22 is rotatably journaled at one end to the end plate 9 and is provided, at the other end, with a central bore 23, (see Figs. 2 and 3) into which the reduced end 24 of the operating shaft 25 extends in such manner as to serve as a bearing support for the switch shaft. The operating shaft 25 is journaled in the end plate 10, and its outer extremity is provided with an operating lever 26 for the purpose of imparting motion to the operating shaft. From the foregoing it will be seen that the operating shaft and the switch shaft are axially aligned and may be relatively rotated.
- Referring to Figs. 3 and 4, the switch unit of the apparatus includes the shaft 22 and a pair of switch members 23a mounted upon the shaft in spaced relation. The switch members are so positioned that they rotate in the transverse planes of the contact members and may be oscillated between them. Each switch member includes a clamping member 27 secured to the shaft 22 and which is provided with a clevis at its upper end, in which a pair of contact supports 28 are pivotally mounted for rotation about the pins 29. The upper ends of the supports 28 carry the switch contacts 30 and 31 and the lower ends are provided with inwardly directed webs 32 which are adapted to engage the edges of the clamp member 27. The contact supports 28 are yieldingly held in a predetermined position with respect to the clamp member by means of a compression spring 33 which is mounted between the supports 28 and which tends to separate the contact members 30 and 31. The outward movement of the supports 28 is limited by the webs 32 which abut against the edges of the clamp member 27 when the spring 33 is distended. The clamp 27 is rigidly secured to the shaft 22 by means of the bolts 34. The contact members 30 and 31 are connected to the bolts 34 by flexible conductive strips 35 and each bolt 34 is connected to a separate terminal 36 by means of a flexible conductor 37. (See Fig. 1.)
- From the foregoing it will be seen that the switch contact 30 will engage the contact member 20 when the switch member 23a is moved to the right and that the switch contact 31 will engage the contact member 21 when the switch member is moved to the left.
- In order to reduce the destructive arcing to a minimum, it is well known that the contact members should be instantly separated in the operation of the switch. In the particular application for which this mechanism is intended, it is necessary to connect one terminal with another with the greatest rapidity in order that the sequence of operation of the apparatus controlled thereby shall not be detrimentally affected. It is an object of this invention, therefore, to withdraw the switch member from a contact member and move it into engagement with the opposite contact member with a quick snap. To accomplish this function, the operating shaft 25 is connected to the switch shaft 22 by a flexible connection which will permit relative movement of the shafts. The switch member is held in engagement with the contact member by a latch adapted to be released by engagement with the member carried by the operating shaft when the latter has moved a predetermined distance. The principle of operation is, therefore, that rotary movement of the operating shaft first exerts a tension upon the switch member tending to withdraw it from engagement with the contact member. The spring is stretched as the operating shaft is rotated until the latch is tripped and the switch member is released. The latter then snaps into engagement with the contact member in an effort to resume its original position with respect to the operating lever.
- The mechanism for accomplishing this operation includes a switch shaft crank 38 which is so mounted upon the square end 39 (Figs. 2 and 3) of the switch shaft 22 that movement of the crank imparts rotative movement to the switch shaft and to the switch member 23a mounted on the latter. The operating shaft 25 is provided with a crank member 40 which is secured thereto, against relative movement, by a pin 41. (See Fig. 2.) The cranks 38 and 40 are provided with crank pins 42 and 43, respectively, which, when the operating shaft and the switch shaft are in normal operative relation, overlap one another and occupy the same radial plane, the pin 43 being closer to the axis of the shaft than the pin 42.
- The cranks 38 and 40 are flexibly connected by means of a pair of bell-crank levers 44 and 45 which are pivoted for rotation on the shaft 25 and arranged relatively in closed relation in the manner of pivoted tongs, the upper extensions 46 and 47, respectively, thereof occupying positions on opposite sides of the crank pins 42 and 43. The lower extensions 48 and 49 of the bell-crank levers 44 and 45, respectively, are located on opposite sides of a plane traversing the axes of the shaft 25 and the crank pins 42 and 43. The upper extension of each lever is positioned at the side of said plane opposite to that occupied by the lower extension thereof, and the levers are connected by means of a tension spring 50 which tends to draw the upper and lower extensions of

the bell-crank levers into closer relation. The movement, however, is limited by the engagement of the upper extremities 46 and 47 with the crank pins 42 and 43 which lie between the said extremities. By reason of this arrangement, the switch members 23a, and the movable contact members 30 and 31 that are supported thereby will normally occupy a predetermined relation with respect to the operating lever 26 and it will be seen that, if the shaft 25 and the operating crank 40 which is attached thereto are moved counter-clockwise, the crank pin 43 carried thereby will positively engage the extension 47 and cause counter-clockwise turning of the bell-crank lever 45, which, in turn, will cause turning of the bell-crank lever 44 through the medium of the spring 50. The switch-shaft crank 38 is turned similarly by reason of the engagement of the extension 46 with the pin 42 that is carried by the switch-shaft crank 38. Further, by reason of the above arrangement, turning of the operating shaft in a counter-clockwise direction is possible even though the movement of the switch-shaft crank 38 be prevented. In this event, the bell-crank lever 44 remains stationary while the bell-crank lever 45 turns with the operating crank 40. This operation causes the spring 50 to be stretched but the tension tending to turn the bell-crank lever 44 in a clockwise direction is not increased, for the reason that, as the arm 49 turns about the shaft 25, the line of stress or the centerline of the spring is moved toward the shaft and, consequently, the leverage is sufficiently reduced to compensate for the increased tension of the spring. It will be apparent, therefore, that the pressure exerted by the upper lever 46 upon the pin 42 to withdraw the switch contact 30 from engagement with the contact 20, is maintained substantially uniform throughout the movement of the bell-crank lever 45. If the increased tension of the spring were not thus compensated, the switch contacts might be actuated with such force that the impact with the stationary contact members would be destructive. When the switch-shaft crank is released while the lower extremities of the bell-crank levers are separated, as above indicated, the bell-crank lever 44 instantly snaps into its original relative position with the crank pin 43. All that remains, therefore, to complete the switch mechanism is the latching means for holding the switch member in operative engagement with either contact, and the means actuated by the operating shaft for tripping the latch after the operating lever has moved to place the spring 50 under tension. The latch mechanism includes a latch member 51 (Figs. 1 and 7) having an upwardly directed tripping arm 52 and a pair of pawl extensions 53 and 54. The latch member is pivoted to the end plate 10 (Fig. 2) upon a stud shaft 55 which is riveted at one end to the end plate 10 and which carries the latch member 51 at its inner extremity. The latch is retained in position on the shaft by means of a screw 56. The upper end of the switch-shaft crank 38 is provided with an integral lug 57 (see Fig. 7) which is adapted to be engaged, on its respective sides, by the pawl members 53 and 54 of the latch 51. As shown in Figs. 1 and 6, the pawl is in engagement with the left side of the lug and serves to prevent separation of the switch contact 30 from engagement with the contact member 20. Fig. 7 shows the position of the elements when the switch contact 31 is moved into operative engagement with the contact member 21. When the switch member occupies the position indicated in this figure, the pawl 54 engages the right side of the lug 57 and prevents separation of the said contact members. The latch is retained in either extreme position thereof by means of a helical spring 58 which is pivoted, at its upper end, to a pin 59 carried by the latch member 51, and, at its lower end, to a pin 60 carried by the switch-shaft crank 38.

Referring to Figs. 1 and 7 showing extreme positions of the switch member 23, it will be seen that the spring 58 functions as an "off-center" spring and lies on different sides of the vertical plane cutting the axis of the stud shaft 55, when in different extreme operative positions. Therefore, during the throwing movement of the switch-shaft crank 38, for instance, when the switch member 23a is being moved toward the left from the position indicated in Fig. 1, the spring 58 will exert a stress upon the latch 51, tending to turn it counter-clockwise the instant the pin 60 moves to the left of the line traversing the axes of the stud shaft 55 and the pin 59 carried by the latch 51. This spring, therefore, so functions to tilt the latch from one extreme position to the other that it is always in position to oppose the return of the switch member or switch-shaft crank 38 until the latch pawls 53 and 54 have been positively tripped out of engagement with the lug 57.

The latch is tripped by means of a pair of tripping arms 61 and 62 which are secured to the operating crank 40. Fig. 6 shows two intermediate stages of the operation of moving the switch member 23 from the position indicated in Fig. 1 to the position indicated in Fig. 7, and, by reference thereto, it will be seen that the full lines indicate the relative position of the operating crank 40, the switch crank 38 and the latch 51 when the tripping arm 61 engages the latch arm 52. In this position, movement of the switch-shaft crank 38 and, consequently, the switch, is prevented by the

1 pawl 53. The broken lines indicate the position of the above-referred-to elements at the time when further movement of the operating crank has so moved the latch that 5 the pawl 53 has just cleared the lug 57 on the switch-shaft crank 38. The operating crank 40, at this time, occupies nearly its extreme position to the left and is in position to draw the switch member to the position 10 indicated in Fig. 7, wherein the switch contact 31 is in complete operative engagement with the contact member 21.

The relative strengths of the springs 50 and 33 are such that the compression of the 15 spring 33, during the engagement of a switch contact with its respective contact member, does not overcome the tension of the spring 50 which continues to hold the bell-crank levers 44 and 45 in engagement with the pins 20 42 and 43, as indicated in Figs. 1 and 7.

Referring to Figs. 2 and 5 wherein the operating means for throwing the switch are illustrated, the operating mechanism consists of the lever 26, to the extreme end of which 25 is suspended, by means of a cable 63, a counterweight 64 which tends to hold the switch elements in the position indicated in Fig. 1. A coil spring 65 surrounds the outer end of the operating shaft 25, and the ends 66 and 30 67 thereof respectively engage lugs 68 and 69 carried, respectively, by the end plate 10 and the lever 26. The spring is so coiled that it tends to turn the operating shaft in a counter-clockwise direction, as indicated by 35 the arrow. The counter-weight, however, is of sufficient weight to overcome the tension of the spring and to hold the lever in the position indicated in Fig. 5, wherein the switch elements occupy the positions indicated 40 in Fig. 1.

The switch member is moved to the left by reason of the action of the spring 65 when a lifting member 70, carried by some 45 part of the hoisting apparatus, raises the counter-weight, in accordance with a familiar practice. The movement of the lever 26 is limited between the stops 71 and 72, the former limiting the movement of the operating shaft in a clockwise direction and the latter limiting the movement of the said 50 shaft in the opposite direction.

It has previously been stated that, in the present embodiment of the invention, there 55 are two separate switch elements mounted on the switch shaft 22, each of which is provided with contact members 30 and 31 and that there are two separate stationary contact members 20 mounted on the supporting bar 13 and two separate stationary contact members 21 mounted upon the supporting bar 14 and so disposed that they will be separately engaged by the contact members 30 and 31 of the switch members, respectively.

60 Referring to Figs. 1 and 2 for the purpose of illustration, the conductors connected to

the contact members 20 are indicated by the numerals 73 and 74; the conductors connected to the contact members 21 are indicated by numerals 75 and 76, and the conductors connected to the switch contact members 30 70 and 31 are indicated by numerals 77 and 78.

The manner in which the switch contact members and terminals are related to the motor and its controlling system is indicated diagrammatically in Fig. 8, wherein 75 the contact members and the conductors connected thereto are given their respective identifying numerals. The above-described limit-switch mechanism is operated in co-operation with a controller switch not described in detail but indicated in the diagram as having four switch elements A, B, C and D, and for the normal hoist-elevating operation the switches are made to assume the relation indicated in the diagram. 80 During the operation, current flows through the conductors 79 and 80, the switch A, the conductor 73, the contact member 20, the contact member 30, the conductor 77, the motor armature 81, the conductor 78, the 85 contact members 30 and 20, the conductor 74, the switch B, the conductor 82, the series field winding 83 of a hoisting motor, a magnetic brake coil 84, a series resistor 85 and a main switch 86. When the operating 90 member 70 carried by the hoist lifts the counter-weight 64, the spring 65, being normally under tension turns the operating shaft 25 counter-clockwise and withdraws the contact members 30 from engagement 95 with the contact members 20 and moves the contact members 31 into engagement with the contact members 21, as previously described. The separation of the contact members 20 and 30 breaks the circuit 100 through the conductor 73 and the closure of contact members 21 and 31 establishes 105 a closed circuit through the armature 81 and the series field winding 83 (see Fig. 8), which creates a dynamic-braking effect, 110 tending to resist further rotation of the armature, in accordance with a familiar practice. The magnetic-braking action is augmented by the dynamic-braking action 115 set up in the motor the instant the switch has been operated. The motor is thus 120 brought to rest within the safety limits. The limit-switch contact members just enumerated are, at this time, in a position that will not interfere with the reversal of the current through the armature when the controller switches A and B are opened and the switches C and D are closed to produce the reverse movement of the hoist, as will 125 be evident from an inspection of Fig. 8.

The instant the operating member 70 (see Fig. 5) recedes from its position in supporting engagement with the counter-weight member 64, the limit switch is returned to its original position, in accord- 130

ance with the previously described normal effect of the counterweight. It will be seen from an inspection of Fig. 8 that the current through the armature at this time, by reason of the above-noted closure of switches C and D flows in a direction tending to operate the motor in a direction opposite to the original direction of rotation of the motor during the hoisting operation. From the foregoing, it will be evident that our limit switch in no way interferes with the normal functions of the controller switches and only comes into operation in the event that the hoist is raised above a safe or determined limit.

While we have described and illustrated but one embodiment of our invention, it will be apparent to those skilled in the art that various changes, modifications, substitutions, additions and omissions may be made in the apparatus described without departing from the spirit and scope of the invention, as set forth by the appended claims.

We claim as our invention:

1. A circuit interrupter comprising a terminal contact member, a switch member adapted to be moved into and out of engagement with the said contact member with a rolling motion, yielding means for moving the switch member out of operative relation with the contact member, and means for latching the switch member in operative relation with the contact member under substantially constant contact pressure and adapted to be released by the said switch-member-moving means to permit sudden movement of the switch member when the said moving means has moved a determined distance.

2. A circuit interrupter comprising a terminal contact member, a switch member adapted to be moved into and out of engagement with the said contact member, means for normally holding the said switch member in operative relation with the said contact member under substantially constant contact pressure, an operating means for the switch member adapted to exert tension upon the switch member tending to disengage the said member from the contact member without relieving the contact pressure when the operating means is moved and to trip the said holding means when the operating means has traveled a determined distance to permit the switch member to move quickly in response to the tension applied by said operating means.

3. A limit switch comprising a terminal contact member, a contactor type switch member adapted to be moved into and out of engagement with the said contact member, a latch member adapted to move into engagement with the switch member when the latter is moved into engagement with the contact member for preventing separation of

the switch from the contact member, means for moving the switch member out of operative relation with the contact member and adapted to release the said latch member when moved a determined distance in a direction tending to withdraw the switch member from the contact member and means for automatically restoring said switch members.

4. A contactor switch mechanism comprising a pair of separate terminal contact members, a terminal, a switch member for separately engaging the said contact members and for connecting the said terminal separately with the contact members, an operating means for the switch member having a spring connection thereto and adapted to stress the said switch member into engagement with the said contact members, latching means for preventing the separation of the switch member from a contact member until the operating means has stressed said spring and means for insuring the restoration of said switch member.

5. A switch mechanism comprising a pair of separate switch contact members, a switch member adapted to be moved into separate engagement with the said contact members, latching means engaging the switch member for normally holding it in engagement with either contact member, a pair of switch-operating members one of which is adapted to move the switch into engagement with one contact member and the other of which is adapted to move the switch member into engagement with the other contact member, tension means normally holding the said operating members in a predetermined relation with respect to the switch member, means for moving one operating member independently of the other in opposition to said tension means and adapted to release the said latching means when moved a determined distance and thereby permit the other operating member to withdraw the switch member from engagement with the contact member in response to the action of the said tension means.

6. A switch mechanism comprising a pair of separate switch contact members, a switch member adapted to be moved into separate engagement with the said contact members, latching means engaging the switch member for normally holding it in engagement with either contact member, a pair of switch-operating members one of which is adapted to move the switch into engagement with one contact member and the other of which is adapted to move the switch member into engagement with the other contact member, tension means normally holding the said operating members in a predetermined relation with respect to the switch member, means for moving one operating member independently of the other in opposition to

6
said tension means and adapted to release the said latching means when moved a determined distance and thereby permit the other operating member to move the switch member out of engagement with one contact member and into engagement with the other contact member in response to the action of the said tension means.

7. A switch mechanism comprising a pair 10 of separate switch contact members, a switch member adapted to be moved into separate engagement with the said contact members, latching means adapted to move into engagement with the switch member when the latter is moved to operative engagement 15 with either contact member and to normally prevent withdrawal of the switch member from the contact member with which it is engaged, a pair of yieldingly connected 20 switch-operating members, each responsive to movement of the other, and means for releasing the said latching means from engagement with the switch member when one of the operating members has moved a predetermined distance.

8. A switch mechanism comprising a switch contact member, a switch member adapted to be moved into and out of engagement with the contact member, a switch-operating member adapted to move the switch member into engagement with the contact member, a switch-operating member adapted to move the switch member out of engagement with the contact member, yielding means connecting the said operating members whereby the said members are made responsive to movements of one another, and means for preventing the movement of one member until the other has 40 moved a predetermined distance.

9. A limit-switch mechanism comprising a contact member, a switch member adapted to be moved into and out of engagement with the contact member, a spring-actuated 45 means for moving the switch member in one

direction, a gravity-actuated means for actuating the switch member in the opposite direction, and latching means for holding the switch member in an operative position and responsive to a determined movement of the said switch-member-actuating means and means comprising said gravity actuated means for restoring said switch member.

10. A switch mechanism comprising a 55 pair of separate contact members, a switch member adapted to separately engage the said contact members, a pair of yieldingly-connected operating members for the switch member having a lost-motion connection therewith, means for separately actuating the said operating members to impart movement to the switch member, and means for arresting movement of the switch member until the operating members have been relatively displaced a predetermined distance.

11. A switch comprising two separate contact members, a switch member adapted to separately engage the contact members, a oscillatable latch adapted to engage the 70 switch member and normally retain it in operative engagement with either contact member, an operating member, a pair of tripping arms carried thereby for selectively engaging the latch and releasing the 75 switch member when the said operating member is moved a predetermined distance toward an extreme operating position thereof, and a yielding connection between said operating member and the switch member 80 adapted to withdraw the switch member from contact with a snap action when the latch is moved to releasing position by the operating member.

In testimony whereof, we have hereunto 85 subscribed our names this 21st day of June, 1920.

CHARLES H. HODGKINS.
FRED M. PARKS.
